UNITED STATES PATENT OFFICE

164,008

LICENSE PLATE HOLDER

Richard N. Loyd, Signal Hill, Calif., assignor of
one-half to Omer D. Johnson, Anaheim, Calif.

Application May 1, 1950, Serial No. 9,619

Term of patent 14 years

(Cl. D14—6)

To all whom it may concern:

Be it known that I, Richard N. Loyd, a citizen of the United States, residing at Signal Hill, State of California, have invented a new, original, and ornamental Design for a License Plate Holder, of which the following is a specification, reference being had to the accompanying drawing, forming a part hereof.

Figure 1 is a front elevational view of a license plate holder, showing my new design;

Figure 2 is a rear elevational view of the license plate holder;

Figure 3 is an end elevational view of the license plate holder; and

Figure 4 is a vertical cross-sectional view of one side of the license plate holder taken on the line 4—4 of Figure 1.

I claim:

The ornamental design for a license plate holder, as shown.

RICHARD N. LOYD.
